UNITED STATES PATENT OFFICE

ALBERT JOSEPH CASSAVANT, OF WHITE BEAR LAKE, MINNESOTA

AIR-PREHEATING ATTACHMENT FOR FURNACES

Application filed October 1, 1928. Serial No. 309,470.

This invention relates to an air preheating attachment for furnaces, and has for its object to provide, in a manner as hereinafter set forth, an attachment of such class for connection with a furnace door to provide for the preheating of the air supplied through the draft device on the door, whereby the air when discharged into the fire box or chamber will be thoroughly heated to facilitate the combustion of the fuel.

Further objects of the invention are to provide, in a manner as hereinafter set forth, an air preheating attachment for the purpose referred to, which is simple in its construction and arrangement, strong, durable, thoroughly efficient in its use, readily installed with respect to the furnace door, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a vertical sectional view illustrating the attachment in position with respect to the door of the furnace.

Figure 2 is a front elevation of the attachment.

Figure 3 is a rear elevation thereof.

Figure 4 is a section on line 4—4, Figure 2.

Figure 5 is a section on line 5—5, Figure 2.

Figure 6 is a section on line 6—6, Figure 1.

Referring to the drawings in detail, 1 indicates a furnace door formed with an offset portion 2, provided with draft openings 3 and which open into a chamber 4, having arranged therein a regulating element 5 pivotally supported from the offset portion 2 and manually operated. The elements 2 to 5, both inclusive, are shown by way of example to provide a controllable draft device on the door 1. The air supplied to the

openings 3 passes into the chamber 4 and is discharged into the attachment, to be presently referred to, which is secured against the inner face of the door 1 and projects inwardly therefrom a substantial distance.

An air preheating attachment, in accordance with this invention, comprises an open front housing consisting of a pair of end walls 6, 7, a top wall 8, a bottom 9 and a rear wall 10, which is of less height than the open front of the housing. The rear terminal portion of each of the end walls is of tapered formation, as indicated at 11, and the rear terminal portion of the top wall 8 extends downwardly, as at 12, and merges into the rear wall 10. The rear terminal portion of the bottom 9 is extended upwardly at an inclination, as at 13 and merges into the rear wall 10. The end walls 6 and 7 are integral with the top, bottom and rear walls of the housing. The forward end of the top wall 8 has formed integral therewith a pair of spaced forwardly extending apertured lugs 14, through which extend hold fast devices 15 for detachably securing the top of the attachment to the door 1. The forward end of the bottom 9 is provided with a pair of depending apertured lugs 16, through which extend hold fast devices 17 for detachably securing the bottom of the housing to the door 1. The hold fast devices 15 and 17 extend through the door 1 and when acting to secure the housing in position, the latter is arranged to have its forward open end receive the air from the chamber 4.

Formed integral with the lower face of the wall 8, forwardly of the portion 12 of the latter, and arranged in spaced relation is a pair of depending ribs 18, 19, which extend from one end wall to the other. The rib 18 is positioned rearwardly with respect to the open front of the housing. Formed integral with the upper face of the bottom 9, forwardly with respect to the portion 13 thereof and arranged in spaced relation, is a pair of upwardly projecting ribs 20, 21, extending from one end wall to the other. The rib 18 is arranged in superposed alignment with respect to the rib 20, and the ribs 19, and 21 are arranged in a similar manner. Formed in-

tegral with the end walls 6, 7, is a pair of superposed, spaced bars 22, 23, the former is arranged below and in alignment with the rib 19 and the latter is arranged above and in alignment with the rib 21.

6 Positioned forwardly of and arranged against the ribs 18, 20, is a combined baffle and partition plate 24, and which is fixedly secured in position by hold fast devices 25 extending through the plate and engaging in the ribs 18, 20. The plate 24 has each end thereof cut away for a portion of its width, as indicated at 26 and 27 to form air outlets, and said portions 26 and 27 are diagonally disposed with respect to the plate. The outlets are indicated at 28, 29 and permit the air to pass from a shallow cold air receiving chamber 30, which is formed by the plate 24, the housing and the door 1 and into which 15 opens the chamber 4. The plate 24 forms the rear wall of chamber 30.

Supported by the bars 22, 23 and extending from the inner face of the plate 24 to the inner face of the rear wall 10 is a horizontally disposed partition 31 which also abuts the inner faces of the end walls 6 and 7. The partition 31 is secured to the plate 24 at the longitudinal median of the latter, by the hold fast devices 32. Seated on the 20 partition 31 and secured to the rib 19 and bar 22, forwardly thereof, is a combined partition and deflector plate 33, which extends from the end wall 7 and terminates at a point removed from the end wall 6 to 25 provide an air outlet passage 34. Hold fast devices 35 are employed for securing the plate 33 to the rib 19 and bar 22. The plate 33, in connection with the partition 31, plate 24 and housing, forms an air heating compartment 36. Seated on the bottom 9 and secured to the rib 21 and bar 23, forwardly thereof, as well as abutting against the lower face of the partition 31 is a combined partition and deflecting plate 38, which extends from the end wall 6 and terminates at a point removed from the end wall 7 to provide an air outlet passage 39. Hold fast devices 40 are employed for securing the plate 36 to the rib 21 and bar 23. 40 The plate 36, in connection with the partition 31, plate 24 and housing, provides an air heating compartment 41 arranged below the compartment 36. The partition 31, rearwardly of the plates 33 and in connection 45 with these latter and the housing, forms a pair of superposed air heating compartments 42, 43. The upper part of the rear wall 10 is provided with a series of ports 44 constituting discharge outlets for the air from the compartment 42 and the lower part of the rear wall 10 is provided with a series of ports 45 constituting discharge outlets for the air from the compartment 43.

65 The passage 28 provides an outlet for the chamber 30 and an inlet for the compartment

36. The passage 29 provides an outlet for the chamber 30 and an inlet for the compartment 41. The passage 34 provides an outlet for the compartment 36 and an inlet for the compartment 42. The passage 39 70 provides an outlet for the compartment 41 and an inlet for the chamber 43. As the air supplied to the chamber 30 is deflected into the compartments 36 and 41 and from said compartments deflected into the compartments 42, 43, the air is thoroughly heated, due to the number of heat radiating surfaces formed by the walls of the several compartments. The air enters a compartment 36 or 41 at one end and is discharged therefrom at the other end. The air enters compartments 42, 43 at opposite ends with respect thereto and is discharged from such compartments in jet-like form into the fire box or chamber.

80 The attachment provides for a thorough preheating of the air before it is discharged into the fire box or chamber, and it is thought the many advantages of an air preheating attachment, constructed in accordance with this invention, can be readily understood, and although the preferred embodiment of the invention is as illustrated and described, yet it is to be understood that changes in the details of construction can be had which 90 will fall within the scope of the invention as claimed.

95 What I claim is:—

1. An air preheating attachment for furnaces comprising a cold air receiving chamber including a rear wall provided at each end with an air outlet passage, said passages diagonally disposed with respect to said wall, a pair of superposed air heating compartments arranged rearwardly of said wall and each having one of said passages opening therein at the front thereof, the rear of each of said compartments formed with an air outlet passage, a pair of superposed air heating compartments arranged rearwardly of the said other pair of compartments and each receiving air at the front thereof from the outlet passage of one of such compartments, and each of the compartments of the last mentioned pair having a series of discharge outlets at the rear thereof.

110 2. An air preheating attachment for furnaces comprising an open front housing, a vertically disposed combined partition and deflector plate secured therein and providing a cold air receiving chamber, said plate having a portion of each end thereof cut away to provide an outlet passage, said passages diagonally disposed with respect to said plate, means arranged within said housing and in connection with the latter and said plate to provide two pairs of superposed air heating compartments, one pair arranged rearwardly of the other and with each of the compartments of the forward pair receiving

air at one end of its front through one of said passages and discharging air at one end of its rear into a compartment of said rear pair, and said housing provided at its rear with discharge ports for each of the compartments of the rear pair of compartments.

3. An air preheating attachment for furnaces comprising two pair of superposed air heating compartments, one pair arranged forwardly of the other and each communicating at one end with one of the compartments of the rear pair, the upper compartment of the forward pair communicating with the upper compartment of the rear pair at an end opposite that end with which the lower compartment of the forward pair communicates with the lower compartment of the rear pair, a cold air receiving chamber common to the compartments of the forward pair and communicating at its ends with such compartments, the point of communication between the chamber and the upper compartment of the forward pair being above and at an opposite end with the point of communication of said chamber with the lower compartment of the forward pair, and means to provide discharge ports for each of the compartments of the rear pair at the rear thereof.

4. An air preheating attachment for furnaces comprising two pair of superposed air heating compartments, one pair arranged forwardly of the other and each communicating at one end with one of the compartments of the rear pair, the upper compartment of the forward pair communicating with the upper compartment of the rear pair at an end opposite that end with which the lower compartment of the forward pair communicates with the lower compartment of the rear pair, a cold air receiving chamber common to the compartments of the forward pair and communicating at its ends with such compartments, the point of communication between the chamber and the upper compartment of the forward pair being above and at an opposite end with the point of communication of said chamber with the lower compartment of the forward pair, and means to provide discharge ports for each of the compartments of the rear pair at the rear thereof, the rear portion of each of the compartments of the rear pair of compartments being of less height than the forward portion thereof.

In testimony whereof, I affix my signature hereto.

ALBERT JOSEPH CASSAVANT.
